UNITED STATES PATENT OFFICE.

CHARLES A. CADWELL, OF CLEVELAND, OHIO, ASSIGNOR TO THE ELECTRIC RAILWAY IMPROVEMENT COMPANY, OF CLEVELAND, OHIO, A CORPORATION OF OHIO.

RHEOSTAT.

1,290,075.

Specification of Letters Patent.

Patented Jan. 7, 1919.

Application filed May 10, 1917. Serial No. 167,685.

To all whom it may concern:

Be it known that I, CHARLES A. CADWELL, a citizen of the United States, and a resident of Cleveland, county of Cuyahoga, and State 5 of Ohio, have invented a new and useful Improvement in Rheostats, of which the following is a specification, the principle of the invention being herein explained and the best mode in which I have contemplated applying that principle, so as to distinguish it 10 from other inventions.

The present improved rheostat is designed for use in connections which require the interposition of a variable amount of resistance, and where such resistance may require 15 to be considerable. At the same time it is desired that the rheostat be portable, so that it must not only be kept within reasonable compass, but also not be so heavy but that 20 two men can carry the same. To the accomplishment of the foregoing and related ends, said invention, then, consists of the means hereinafter fully described and particularly pointed out in the claims.

25 The annexed drawing and the following description set forth in detail certain mechanism embodying the invention, such disclosed means constituting, however, but one of various mechanical forms in which the principle 30 of the invention may be used.

In said annexed drawing:—

Figure 1 is a side elevational view of a 35 rheostat embodying my present improvements, a portion of the wire screen which in- closes the coils of the rheostat being sectioned away and the coils themselves being in the main shown diagrammatically; Fig. 2 is a top plan view of the same; Fig. 3 is a trans- 40 verse section of a detail, the plane of the sec- tion being indicated by the line 3—3, Fig. 2; and Fig. 4 is a diagrammatic view of the ap- paratus.

The resistance element, proper, consists of a spirally arranged helical coil 1 of wire, 45 preferably of Monel metal, as offering the greatest resistance for a given cross-section. The several convolutions of this coil, as clearly shown in Figs. 1 and 2, are arranged 50 to engage with the inner faces of a plurality of parallel vertical standards joined at their respective upper and lower ends by frames 2 of general oval shape, so as to surround a hollow space.

These standards, in the preferred form 55 illustrated, are built up of central rods 3,

upon which are mounted a series of insulator spools 4 held spaced from the end-frames 2, and from each other, by means of collars 5 of less diameter, which are preferably, although not necessarily, of insulating mate- 60 rial. The collars between the endmost spools and the adjacent frame are of varying lengths, so that the spools will be disposed in spiral fashion to properly receive and hold the convolutions of the resistance coil. The 65 tension of the latter may be relied upon to hold the coils in contact with these spools, although provision may be made to tie them thereto, at least in places, if desired. Since the tendency, however, of the coil, when 70 heated, is to expand, it will remain all the more securely in place when current is actu- ally being passed through the rheostat, in contradistinction to an arrangement where the convolutions of the coil surround the sup- 75 porting standards, or other kind of frame.

In order to vary the amount of resistance in the circuit a series of plug-sockets 6 is provided, each connected with the coil 1 at a different point by branch conductors 7, so 80 that by inserting the end of the one main lead 8 in one or the other of these sockets, a correspondingly greater or smaller resistance will be introduced in the circuit. The form of the sockets is clearly shown in Fig. 3, and 85 for convenience they are disposed in a line across the upper frame 2, being embedded in suitable insulating material 9 held between angle bars 10. Included in the connection from the other lead to the coil is an 90 automatic switch 15 of the breaker type which is designed to interrupt the circuit whenever the current becomes excessive in volume.

For carrying the apparatus about, two pair 95 of handles 11 are attached to the upper frame 2 at rectangularly related points, such handles being thus attached to pivots 12, that allow them to normally depend vertically alongside the apparatus. The inner, shorter 100 ends 13 of the handles, however, are ar- ranged to interlock with the bars 14, which provide specific means for their attachment to the frame, when such handles are raised into horizontal position, and, in the latter 105 position of the handles two operators can readily carry the apparatus between them, by each one grasping a pair of the handles.

Other modes of applying the principle of my invention may be employed instead of 110

the one explained, change being made as regards the mechanism herein disclosed, provided the means stated by any of the following claims or the equivalent of such stated 5 means be employed.

I therefore particularly point out and distinctly claim as my invention:—

1. In a device of the character described, the combination with a plurality of parallel 10 insulating standards surrounding a hollow space, each of said standards comprising a central rod and a series of insulator spools mounted thereon; of a helically arranged coil of resistance wire disposed in the space 15 inside of said rods and contacting with said spools, so as to be supported thereby, said spools being disposed in spiral fashion on said rods, substantially as described.
2. In a device of the character described, 20 the combination of end frames of general oval form; a plurality of parallel rods con-

necting said frames and so surrounding a hollow space; a series of insulator spools on each of said rods, the spools on successive rods being disposed in spiral fashion; and a helically arranged coil of resistance wire disposed in the space inside of said rods and contacting with said spools so as to be supported thereby. 25

3. In a device of the character described, the combination with a plurality of parallel insulating standards surrounding a hollow space; of a helically arranged coil of resistance wire disposed inside of and contacting with said standards, so as to be supported thereby; and a plurality of contacts respectively connected with the ends of said coil and at points intermediate of such ends, substantially as described. 30 35

Signed by me, this 4 day of May, 1917.

CHARLES A. CADWELL.
